(57) **CLAIM**

The ornamental design for a height indicator, as shown and described.

DESCRIPTION

FIG. 1 is a perspective view of a height indicator embodying our design;

FIG. 2 is a front elevational view thereof;

FIG. 3 is a top view thereof;

FIG. 4 is a bottom view thereof;

FIG. 5 is a right side elevational view thereof;

FIG. 6 is a left side elevational view thereof;

FIG. 7 is a side view of the height indicator in FIG. 1 shown on a basketball goal support apparatus; and,

FIG. 8 is another side view of the height indicator in FIG. 1 shown on a portion of a basketball goal support apparatus. The broken lines shown in the Figures are for illustrative purposes only and form no part of the claimed design.
